(57) **CLAIM**

The ornamental design for an indoor data connectivity cabinet with surface ornamentation, as shown and described.

DESCRIPTION

FIG. 1 is a front perspective view of a first embodiment of an indoor data connectivity cabinet with surface ornamentation showing our new design;

FIG. 2 is a bottom plan view thereof;

FIG. 3 is a top plan view thereof;

FIG. 4 is a left side elevation view thereof;

FIG. 5 is a right side elevation view thereof;

FIG. 6 is a front elevation view thereof;

FIG. 7 is a rear elevation view thereof;

FIG. 8 is front perspective view of a second embodiment of an indoor data connectivity cabinet with surface ornamentation showing our new design;

FIG. 9 is a bottom plan view thereof;

FIG. 10 is a top plan view thereof;

FIG. 11 is a left side elevation view thereof;

FIG. 12 is a right side elevation view thereof;

FIG. 13 is a front elevation view thereof; and,

FIG. 14 is a rear elevation view thereof.

The dot-dash broken lines and evenly spaced broken lines immediately adjacent to the claim, represent the bounds of the claim, while all other broken lines are directed to environment; the broken lines form no part of the claimed design.
